UNITED STATES PATENT OFFICE.

WALTON HARRISON, OF BROOKLYN, NEW YORK.

RECEIVER FOR WIRELESS COMMUNICATION.

1,116,588

Specification of Letters Patent.

Patented Nov. 10, 1914.

Application filed February 8, 1904. Serial No. 192,624.

To all whom it may concern:

Be it known that I, WALTON HARRISON, a citizen of the United States, and residing at Brooklyn, New York, have invented divers 5 new and useful Improvements in Receivers for Wireless Communication, of which the following is a specification.

Figure 1 is a side elevation of my improved antenna, made up of units connected 10 serially. Fig. 2 is a diagrammatic perspective view of the entire apparatus in action.

A number of posts 4, are arranged in straight rows, the general direction of each row being slightly askew relatively to the 15 path of propagation of the waves, so as to cross the same at an angle, as indicated in Fig. 2. Upon each post is an insulator 5, provided with a seat 6, the several seats in each row being in alinement with each other. 20 The antennæ, or wave collectors, consisting of longitudinal metallic conductors of sinusoidal form, are mounted in the seats as shown. Each antenna is provided at its ends with binding posts 7, 7^a. From the 25 binding post 7 of one antenna, a wire 8 leads to a wave-responsive device, such as a coherer 9. A wire 1 is connected with the wire 8, and with a switch button 11. A similar switch button 12 is in communication with 30 the coherer. A switch arm 13 is connected by a wire 14 with a telephonic receiver 15, from which a wire 16 leads to a battery 17. By moving the switch arm into engagement with the respective buttons, the coherer may 35 at will be cut out of or into the battery circuit. The wire 18 connects the battery with the binding post 7^a of the last antenna of the series. The several antennæ are joined together, preferably in series as shown, by 40 connecting wires 19. I do not limit myself, however, to the serial arrangement, as the antennæ may be connected in other ways. The crests of the several electromagnetic waves are indicated at 20, 21, 22 and 23. I 45 preferably employ Hertzian waves radiated from a vertical oscillator 24, but for many purposes other electromagnetic waves and electric radiations of divers other kinds may be employed successfully.

50 Each antenna, because of its sinusoidal conformity, may, for convenience, be considered as made up of subdivisions *b*, *d*, disposed in different directions, and integrally connected together in series. Since 55 the general length of each antenna is askew

relatively to the direction of propagation of the waves (see Fig. 2), the curves of the antennæ are a little more than a wavelength apart, measured from crest to crest in the general direction of the antenna, in order to maintain them exactly a wavelength apart, as measured in a direct line from the transmitting station.

My purpose in disposing the antennæ askew relatively to the direction of propagation of the waves is to enable each subdivision of every antenna to be acted upon by a different part of each successive wave. As the connecting wires 19 are all "end-on" toward the transmitting station, they are not affected materially by the waves. An observer standing at the oscillator 24, and looking toward the battery of antennæ would apparently behold (aside from the question of distance), each antenna throughout its entire length, and would also see each subdivision of each antenna in the entire battery. He would see, in substance, a single antenna occupying a comparatively large fraction of the horizon. It will be observed that, on account of the several antennæ being disposed askew, no subdivision is in the electrical shadow of any other subdivision. The several subdivisions may therefore be regarded as so many units exposed separately to wave action, yet located half a wave length apart in the general direction of travel of the waves. I find that by this arrangement each unit or subdivision acts to its full capabilities, as if segregated, yet the telephonic receiver or other indicator responds cumulatively to an extent commensurate with the effect of a single unit multiplied by the number of units in the entire system. When the waves 95 arrive from a direction represented by the position of the oscillator 24, and set up surgings in the units of the receiving antennæ, these surgings are in phase with the waves. When, however, the waves arrive 100 from any other direction than the one indicated, the waves arriving and the oscillations set up in the units tend to develop phase differences, and discord is the result. The battery of antennæ as a whole is therefore more sensitive to waves arriving from a certain definite direction than from other directions, and upon this account possesses 105 a sort of selectivity.

Having thus described my invention, I

claim as new and desire to secure by Letters Patent:—

1. A receiver system for wireless signaling, comprising a plurality of antenna members, more than two in number, spaced apart by distances of half a wave length, measured in the direction of travel of the waves and connected in series with each other with respect to oscillation set up in said antenna members.
2. The combination, in a receiver system having a plurality of supports, more than two in number, and spaced apart, of a plurality of antenna members corresponding to the number of supports and connected together in series with each other with respect to oscillations set up in said antenna members, the antennæ being spaced apart in the direction of travel of the waves, by distances of half a wave length.
3. The combination, in a receiver system for wireless signaling, of a plurality of antenna members, more than two in number, the several antenna members being spaced apart, in the direction of travel of the waves, by distances of half a wave length, and being in series with each other with respect to oscillations set up in them.
4. In a receiver system, the combination of a number of units arranged in groups, the several groups being joined together by wires radiating outward on lines having the oscillator as a center, whereby they are prevented from interfering with the action of the units.
5. A receiving antenna comprising a number of receiving units more than two in number, connected in series with each other and spaced apart in a direction crossing the path of travel of the waves, one of said units being spaced farther than another from the source of said waves by a distance of half a wave length.
6. A receiving antenna comprising units, more than two in number, spaced from a transmitting member by distances dependent upon the wave length, said units being also spaced apart in a general direction lateral to the general direction of travel of the waves, and being in series with respect to electrical disturbances set up in them by the energy of said waves.
7. A receiving antenna comprising a number of aerial units in series with each other with respect to electrical disturbances set up in them, by wave action, said units being spaced directly apart in a direction lateral to the path of travel of the waves by distances independent of the wave length, and spaced apart in the direction of travel of said waves by distances dependent upon the wave length.
8. A receiving antenna comprising a number of aerial units in series with each other with respect to electrical disturbances set up therein by wave action, said units being spaced from each other, in a direction lateral to the path of travel of the waves one of said units being spaced farther than another from the source of the waves by a distance of exactly half a wave length.
9. In wireless antennæ, the combination of supports, and a single wire mounted upon said supports and bent to form loops, said loops extending in a plane common to all of them.
10. In wireless antennæ, a single wire bent sinuously into loops, all of said loops being disposed in a single plane.
11. In wireless antennæ, a single wire bent into loops, more than two in number, said loops being disposed in a single plane.
12. In wireless antennæ, a single wire formed into loops, all of said loops being located in a common plane, and fixed supports connected with said wire for preventing said loops from turning.
13. In wireless antennæ, a single receiving wire bent sinuously into loops, and means for supporting said loops in a fixed plane disposed askew relatively to the path of wave propagation.
14. In wireless antennæ, a wire bent sinuously into a plane askew to the path of propagation, in order that various loops may be energized in opposite phase, yet add their energies, said loops being in series.
15. In wireless telegraph antennæ, the combination of suitable supports, and a plurality of wire loops extending horizontally and lying in a vertical plane between said supports, substantially as described.
16. In wireless telegraph antennæ, the combination of a plurality of masts, and a single wire formed into loops extending horizontally and lying in a vertical plane between and supported by said masts, substantially as described.
17. In wireless telegraph antennæ, the combination of a plurality of masts; and a single continuous wire formed into a plurality of loops extending in a vertical plane and supported by said masts, substantially as described.
18. In a system of transmission by electric waves, a terminal apparatus comprising a series of two or more antenna units separated by a distance equal to one wave length of the transmitted waves, and electrically connected together, a series of two or more antenna units separated by one wave length and arranged alternately with the antenna units of the first series, and station apparatus in circuit with the two sets of antenna units.
19. In a system of transmission by electric waves, a terminal apparatus comprising a series of antenna units insulated from the earth and separated by one wave length of the transmitted waves, a similar series of

antenna units insulated from the earth and separated by one wave length and arranged intermediate and at equal distances from the antenna units of the first series, and station 5 apparatus connected in circuit with the respective antenna units.

20. In a system of transmission by electric waves, terminal apparatus comprising a series of antenna units insulated from the 10 earth and alternating with a series of antenna units also insulated from the earth, the said antenna units being located in the line of desired transmission and spaced apart substantially equal to one-half the length 15 of the transmitted waves, and means for simultaneously exciting each series of antenna units with electrical oscillations of opposite sign.

21. In a system of transmission by electric waves, a terminal apparatus comprising antenna units insulated from the earth, means for producing a series of electric waves having their positive portions coinci-

dent and also having their negative portions coincident in the direction of desired transmission but non-coincident in other directions, the electric instrument in circuit having its leads connected with the ends of said antenna units.

22. In a system of transmission by electric waves, a terminal apparatus comprising antenna units, means for producing a series of electric waves having their positive portions coincident and also having their negative portions coincident in the direction 25 of desired transmission but non-coincident in other directions, the electric instrument in circuit having its opposite leads connected with the ends of alternate antenna units.

In testimony whereof I have signed my 30 name to this specification in the presence of two subscribing witnesses.

WALTON HARRISON.

Witnesses:

JOHN LARKIN,
E. C. NIELSON.
